Primary Examiner — Andrew Kerr*Assistant Examiner* — Chariton Alexakis(74) *Attorney, Agent, or Firm* — Daniel M. Cohn; Howard M. Cohn(57) **CLAIM**

The ornamental design for a food container as shown and described.

DESCRIPTION

FIG. 1 is a perspective view of a built-in board of food container showing my new design;

FIG. 2 is another perspective view thereof;

FIG. 3 is a front and back view thereof;

FIG. 4 is a left and right view thereof;

FIG. 5 is a top plan view thereof;

FIG. 6 is a bottom plan view thereof;

FIG. 7 is a perspective view of a main body of food container showing my new design;

FIG. 8 is another perspective view thereof;

FIG. 9 is a front and back view thereof;

FIG. 10 is a left and right view thereof;

FIG. 11 is a top plan view thereof;

FIG. 12 is a bottom plan view thereof;

FIG. 13 is a perspective view of a food container showing my new design, in a split state;

FIG. 14 is a partial enlarged view of portion 14 in FIG. 2; and,

FIG. 15 is a partial enlarged view of portion 14 in FIG. 7. The broken lines depict portions of the food container and form no part of the claimed design.

1 Claim, 15 Drawing Sheets
